Inventor
John O. Nastin

UNITED STATES PATENT OFFICE.

JOHN O. NASLIN, OF SEATTLE, WASHINGTON.

DOOR-CLOSING DEVICE.

1,357,583.

Specification of Letters Patent. Patented Nov. 2, 1920.

Application filed March 22, 1920. Serial No. 367,840.

To all whom it may concern:

Be it known that I, JOHN O. NASLIN, a citizen of the United States, residing at Seattle, in the county of King and State of Washington, have invented a new and useful Door-Closing Device; and I do hereby declare that the following is a full and exact description thereof, reference being had to the accompanying drawings, and to the characters of reference marked thereon.

My invention relates to a door closer, described in my former application, filed November 10, 1919, Serial No. 337,105, which has been abandoned, whereby in combination with a tension spring, a door, or the like, is rendered self-closing in such a manner, as to almost entirely obviate the common defect of spring strain, when the door is swung open; and by which, without other checking means, a door may be rendered self-closing without any serious slamming.

The adapted construction of my invention has been illustrated in the accompanying drawings, and the annexed specification is a detailed description thereof, and the parts for which Letters Patent is desired are more specifically set out in the claims.

Figure 1 is a top view of the door closer, as it appears in position when the door is closed; the dotted line portion indicating the position of the spring, when the door is swung open square with the wall.

The door is indicated by "1", the jamb by "2", and the door hinge by "3".

Fig. 2 is a side view of the device, as seen from the front side of the door; Fig. 3 is a front view as seen from the side of the door, with spring G removed; Fig. 4 is another top view of the device, showing by dotted lines the position of the counter-balance and the spring when the door is swung open way back to the wall, to which it is hinged; and Fig. 5 is a side view of the extension hinge F_a.

In these figures the same letters and numbers refer to the same parts.

The door closer consists principally of a spring-carrying triangular shaped counter-balance, with an extension hinge F_a, braced between the characters A, B, and C, with balance-arm D, and a door closing spring G, and is pivoted to bracket H at A, and at C to arm D, which is in turn pivoted to the side or head piece of the door jamb, in such a manner as to keep the counter-bal-

ance just described, when the last named is properly fastened to the door, in a suitable position, when the door opens and closes.

The construction of these mentioned parts may be varied without in the main varying the principles involved, but must, however, be such as to render the door self-closing in an easy-going manner, when connected thereto with spring G, as indicated on the drawings.

The portion indicated by F between points A and B is curved and considerably wider than the other sides of the counter-balance, and for that reason is held upon pivot A to the door in a more satisfactory manner, than if narrower in width, and also forms a suitable abutment for spring G, and means for its attachment in one or another of holes 1^a, 2^a and 3^a therein, besides means of attachment at point B, by which said spring to some extent may be adjusted, and regulated as to its tension-effect with respect to the closing movement of the door, according to the size and dimension thereof; and at the same time it is held in a suitable position so as to clear the other parts of the door, when the latter opens and closes. Its other end may be fastened onto the door by the simple customary hook-and-eye-manner, at K, so as to give it the proper tension for the automatic closing of the door.

The extension hinge F_a, which forms a matched part of the spring-carrying extremity F, to which it is hinged, and also pivoted to bracket H at A, serves the purpose to extend the sweep of the counter-balance, so as to allow the door free swing, when it is opened way back to the wall to which it is hinged; and thereby, when the door is swung open in that manner, the spring-tension becomes more effective upon the closing movement of the door, as the hinged portion F_a is expanded.

As it will be seen from the foregoing, the essential features of the device consist in its adaptation in minimizing the strain of the spring, which is carried by and with the door in opening, and at the same time becomes more effective when the latter is swung wide open, and when it reaches a closed position, as indicated in Figs. 1 and 4, where the door is shown as swung from a closed to an open position.

Thus the distance from A to B remains the same when the door is opened as when it

- is closed; but when the spring is attached directly to the jamb, the distance from such a point of attachment to point A on the door, will be considerably greater when the door is swung to an open position, than when it is closed, and, consequently, the spring-strain will also be greater, than when the spring is carried along with the door, when it is swung open.
10. This figure, embraced by characters A, B and C, may be constructed differently from that which I have indicated in the drawings, either in one piece, or in separate pieces, and then suitably combined; but it is essential, that the sides, or rather, the distances indicated by letters F, I, J and D between the connecting points A, B, C, and E, C, be such in proportion, as to render the device suited for the purpose for which it is intended; and it should be attached onto the door near to its hinged edge.
- What I claim is:
1. In a door closer, a spring-carrying counter-balance, having a pivoted extremity connected to a hinged movable part, to reciprocally swing with said part, a spring-carrying extremity, extending from said pivoted extremity outwardly to a suitable distance for spring-connection, and provided with spring means for rendering said part self-closing, and means for guiding said spring means clear of the hinged edge of said part when swinging, and means for maintaining said balance in suitable position against the tension of said spring means.
  2. In a door closer, a spring-carrying counter-balance having three opposite pointing extremities, a pivoted extremity, a spring-carrying extremity and a balance-arm extremity, means connecting said pivoted extremity to a hinged swinging part, adjacent its hinged edge, so as to reciprocally swing therewith, a balance-arm and pivot-means connecting said balance-arm extremity to a stationary part, for holding said balance in suitable position with respect to said parts; and a spring connecting said spring-carrying extremity with said hinged part so as to render said part self-closing.
  3. In a door closer, a spring-carrying counter-balance, having a pivoted extremity connected to and reciprocally movable with a hinged part, a spring-carrying extremity extending outwardly from said pivoted extremity to a point suitable for spring-connection, a spring connected thereto so as to render said part self-closing, and means for guiding said spring clear of the hinged edge of said part when swinging, a balance-arm extremity extending forward from said pivoted and spring-carrying extremities to a point suitable for balance-arm connection, and a balance-arm oppositely connecting said balance-arm extremity to a stationary part, for holding said balance in suitable position against the tension of said spring.
  4. In a door closer, a spring-carrying counter-balance pivoted to a hinged swinging part near its hinged edge to reciprocally swing therewith, a forward-pointing extremity adapted for balance-arm connection and means connecting said extremity to a stationary part, for suitably maintaining said balance against the spring-tension actuating said swinging part, a spring-carrying extremity extending outwardly to a point suitable for spring-connection, spring means connected thereto so as to render said swinging part self-closing, and means for guiding said spring means clear of the edge of said swinging part.
  5. In a door closer, a spring-carrying counter-balance, having a hinged portion pivoted to a swinging part near its hinged edge, whereby the sweep of said balance may be expanded so as to facilitate a free opening swing of said part, and a spring-carrying extremity matched and jointed to said portion so as to jointly move therewith and reciprocally swing with said part, a balance-arm extremity and means connecting said extremity and a stationary part to maintain said balance against the spring-tension actuating said swinging part, and a spring connecting said spring-carrying extremity and said swinging part, whereby said part is rendered self-closing.
  6. In a door closer, a spring-carrying counter-balance having a forward pointing balance-arm extremity extending from a spring-carrying and a pivoted extremity, said extremities, and a balance-arm connecting said balance-arm extremity to a stationary part, for maintaining said balance against the spring-tension actuating a swinging part, a spring connecting said spring-carrying extremity and said swinging part, which is thereby rendered self-closing, and a hinged portion connecting said spring-carrying extremity and said swinging part, whereby the free opening swing of said part is facilitated.
  7. In a door closer, a spring-carrying counter-balance, having a spring-carrying extremity matched and hinged to a curved portion pivoted to a swinging part, and adapted to reciprocally swing therewith and facilitate the free opening swing thereof, a forward pointing balance-arm extremity adapted for balance-arm connection, means connecting said balance-arm extremity to a stationary part for maintaining said balance against the spring-tension actuating said swinging part, spring means connecting said spring-carrying extremity to said swinging part, for rendering said part self-closing; and the said portion and means connecting it to the said swinging part.

JOHN O. NASLIN.
